DESIGN FOR A LEATHER OR SIMILAR ARTICLE

Samuel Galper, New York, N. Y.

Application February 17, 1938, Serial No. 75,204

Term of patent 3½ years

To all whom it may concern:

Be it known that I, Samuel Galper, a citizen of the United States, residing in New York city, in the county of the Bronx and State of New York, have invented a new, original, and ornamental Design for a Leather or Similar Article, of which the following is a specification; reference being had to the accompanying drawing, forming part thereof.

The figure is a plan view of leather or similar article, showing my new design.

The characteristic feature of the design resides

in the circular motifs, each comprising a circular button concentrically located within a circle of simulated stitching with a substantially star-shaped figure spacing the button from the surrounding circle, said motif being placed at the common intersection of a series of vertical, horizontal and diagonal ornamented bands.

I claim:

The ornamental design for a leather or similar article, substantially as shown and described.

SAMUEL GALPER.
